UNITED STATES PATENT OFFICE.

EUGENE J. MURPHY, OF PROVIDENCE, RHODE ISLAND.

DESIGN FOR A GRAVE-MARKER.

SPECIFICATION forming part of Design No. 30,813, dated May 16, 1899.

Application filed April 21, 1899. Serial No. 713,977. Term of patent 3½ years.

To all whom it may concern:

Be it known that I, EUGENE J. MURPHY, a citizen of the United States, residing at Providence, in the county of Providence, in the State of Rhode Island, have invented and produced a new and original Design for Grave-Markers, of which the following is a specification, reference being had to the accompanying drawings, forming part thereof.

As shown in the drawings, the features of my design are as follows:

Figure I is a face view, and Fig. II a view in vertical section.

The general outline resembles a Maltese cross with a circular central piece A superimposed. All marginal boundaries *a a* are in relief. The essential feature of the centerpiece is the representation of a soldier B bearing a gun. The two lateral arms *b b* of the cross have their outer edges *c c* scalloped,

while the upper or central arm *c* has a semi-circular crest *d* with a marginal row of thirteen stars. Resting upon the crest is an eagle *e* with extended wings, flanked on either side by a cannon-muzzle *f* and a flag *g*. Extending upwardly from the crest is a flagstaff *h*. In the spaces between the central and lateral arms of the cross are military emblems, on one side two crossed swords C, on the other two guns crossed D.

Having described my invention, what I claim as new, and desire to secure by Letters Patent, is—

The design for a grave-marker, as herein shown and described.

EUGENE J. MURPHY.
